CLAIM

The ornamental design for a rapid mover apparatus and assembly, as shown and described.

DESCRIPTION

FIG. 1 is a perspective of the rapid mover, apparatus and assembly in accordance with an embodiment of the present invention;

FIG. 2 is a top view of the rapid mover apparatus and assembly;

FIG. 3 is bottom view of the rapid mover apparatus and assembly;

FIG. 4 is a side view of the rapid mover apparatus and assembly;

FIG. 5 is a side view of the rapid mover apparatus and assembly;

FIG. 6 is a end view perspective of the rapid mover apparatus and assembly;

FIG. 7 is a end view perspective of the rapid mover apparatus and assembly;

FIG. 8 is a perspective side, cross-sectional view illustrating the fabric and plate construction of the rapid mover apparatus and assembly in accordance with an embodiment of the present invention;

FIG. 9 is a perspective side, cross-sectional view illustrating the flexibility of the fabric and plate construction of the rapid mover apparatus and assembly in accordance with an embodiment of the present invention;

FIG. 10, taken along lines 10 in FIG. 8, is a perspective side, cross-sectional view illustrating the fabric and plate construction of the rapid mover apparatus and assembly in accordance with an embodiment of the present invention;

FIG. 11 is a perspective side view illustrating the folding of the fabric and plate construction of the rapid mover apparatus and assembly in accordance with an embodiment of the present invention; and

FIG. 12 is a perspective view of the operation of a person transporting a load on the rapid mover apparatus and assembly in accordance with an embodiment of the present invention.

The broken lines in the drawings show unclaimed environment only and form no part of the claimed design.
